ARDEN J. MUMMERT, OF ST. LOUIS, MISSOURI, ASSIGNOR TO McQUAY-NORRIS MANUFACTURING COMPANY, OF ST. LOUIS, MISSOURI, A CORPORATION OF MISSOURI.

PISTON-RING.

1,321,539.

Specification of Letters Patent. Patented Nov. 11, 1919.

Application filed February 5, 1918. Serial No. 215,469.

To all whom it may concern:

Be it known that I, ARDEN J. MUMMERT, a citizen of the United States, residing at St. Louis, State of Missouri, have invented 5 certain new and useful Improvements in Piston-Rings, of which the following is a full, clear, and exact description, reference being had to the accompanying drawings, forming a part hereof.

10 The present invention is directed to the manufacture of resilient split packing rings for pistons, the object sought being to produce a ring of substantially uniform cross-section which when inserted into the cylinder in which it is intended to operate will not only conform to the circular cross-section of the cylinder but will engage the walls thereof with uniform pressure throughout its entire circumference. In 15 other words, the object sought is to produce a split metal piston ring which shall be truly circular while in service and which shall exert at all points uniform radial pressure against the walls of the cylinder 20 in which the same is confined. In this type of ring the contact with the cylinder walls is brought about by the outward spring of the metal of which the ring is composed, the radial pressure exerted against said 25 walls depending on the shape of the ring when free (or out of the cylinder), on the cross-section of the ring, and on the resilience of the metal (or other material) from which the ring is made. The circum- 30 ferential dimension of the ring should be sufficient to permit the ring when placed on its piston and deposited in the cylinder, to expand into or assume the form of an annular or circular body whose outer face 35 or periphery shall contact at all points with, and exert equal radial pressure against, the walls of the cylinder. Rings of this character being usually cast, it necessarily follows that the resilience of the metal can 40 be availed of only by splitting or parting the ring and thereby leaving a gap which will permit of sufficient contraction in the ring to impose on the metal the necessary tension under which it tends to resume its 45 original expanded position, this tension being the force which acts radially upon the walls of the cylinder when the contracted ring is inserted thereinto. My invention is 50 specially concerned with the stage at which the gap is formed in the blank from which 55

the ring is directly made, and with the manner of forming the blank. As ordinarily constructed, a packing ring is made by cutting a circular blank or ring of iron of proper width and thickness from a tube 60 casting, the outside diameter of the ring exceeding the diameter of the cylinder bore designed to receive it. This excess in diameter (by way of example) is approximately 65 one thirty-second of an inch for every inch of diameter of the cylinder bore, so that if the diameter of the bore is four inches, the outside diameter of the ring would be four and four-thirty-seconds inches. The rule for the thickness of the ring is also one 70 thirty-second of an inch thickness for each inch of diameter of bore, a cylinder four inches in diameter requiring a ring four-thirty-seconds of an inch in thickness. From this oversize circular blank there is 75 cut a segment, thereby leaving a gap which permits the ring to be contracted or compressed and inserted into the cylinder, the inherent resilience, and tendency of the ring to resume its original dimensions or free 80 state and contour, exerting the necessary radial pressure against the walls of the cylinder, forming a joint therewith, and preventing the escape of any fluid that is to be held by the piston. A ring made in the 85 manner outlined above does not contact with the walls of the cylinder to the same degree at all points, owing to the distortion of the ring from a true circular form when contracted; and in practice the portions of 90 the ring contiguous to the ends on each side of the gap are more or less out of contact so as to leave a clearance between the ring and cylinder walls and permit the gases or fluid to escape therethrough. In this 95 type of ring the greatest radial pressure will be found at the ends and at the mid section, the poorer contact and hence the less pressure being confined to the sections ninety (90) degrees from either of the points 100 of maximum pressure referred to. It is therefore apparent that a piston ring to operate with uniform pressure in the cylinder must not be a perfect circle when free, and conversely if the proper initial curvature be imparted to the ring when free 105 and not contracted or compressed, it will show a uniform pressure per square inch at every point of contact with the cylinder walls, when contracted. In the defective 110

type of ring above alluded to, the error is often corrected by lapping or scraping the outer face of the ring so as to present a more uniform pressure throughout its entire periphery; but this practice consumes time and labor and is for that reason objectionable. In the early stages of development of my present improvement I succeeded in securing uniform radial pressure throughout the entire circumference of a ring by bending a split circular ring at different sections from a very heavy curve at the ends to a very light one at the mid section. The general outline of the ring when free was no longer a true circle, but followed a curve taken from a templet. The templet curve was derived by calculating the stresses at different sections of a hypothetical ring which was assumed to exert the same radial pressure per square inch at all points against the cylinder walls. It was found that these stresses decreased uniformly from the mid section to the ends of the ring, the curve being calculated to so vary the radii at different sections of the ring as to produce a ring which when free was not a true circle. Such a ring when compressed would produce the proper stress relations at different sections so as to exert substantially uniform radial pressure against the cylinder walls along its entire circumference. To bend each ring individually however consumes time and labor, to eliminate which is one of the objects of my present improvement. I avail myself of the curvature of the templet based on the stress calculations of the hypothetical ring aforesaid, but in lieu of imparting this curvature to each individual split circular ring by the bending and straining process above referred to, I provide a suitable pattern from which is cast the blank from which the finished piston ring is directly made. The method by which the pattern for this blank is obtained, as well as the resulting blank and finished ring I consider to be new. The advantages of the invention will be fully apparent from the following detailed description in connection with the accompanying drawings in which—

Figure 1 represents a plan of a conventional circular ring from which a segment has been removed to permit the same to be contracted for insertion into a cylinder, the bore line of the cylinder being shown dotted; Fig. 2 is a plan of the contracted ring confined in the cylinder the latter being shown in cross-section, said view showing the clearance between the cylinder walls and the outer face of the ring on either side of the ends of the ring; Fig. 3 is a plan of the closed pattern ring employed at the initial stage of my method, said ring exceeding in outside diameter the diameter of the cylinder bore designed to receive it, the bore

being shown dotted; Fig. 4 is a plan of the same ring showing the initial saw slot or cut therein, the cylinder bore being dotted; Fig. 5 is a plan of the slit ring shown superposed over the circle defining the bore of the cylinder, the dotted lines representing the deflection to which the ends of the ring are subjected and the distortion from a true circle suffered by the ring in consequence; Fig. 6 is a plan of the distorted ring with the bore line shown dotted; Fig. 7 is a plan of the distorted ring with the saw slot or cut closed by a suitable filler and serving as a pattern; Fig. 8 is a plan of the ring blank cast from said pattern; Fig. 9 is a plan of the ring blank showing the section which is to be cut out and removed to produce the final free or open ring; Fig. 10 is a plan of the completed ring when free and not restrained; Fig. 11 is a plan of the ring shown contracted and confined in the cylinder; and Fig. 12 is a cross-section on the line 12—12 of Fig. 10.

Referring for the moment to Figs. 1 and 2, in which the open ordinary circular ring is represented by the numeral 1 and the cylinder by C, it will be observed that when the ring is contracted and inserted in the cylinder, it becomes distorted from a true circle, the portions between the ends and points 90 substantially ninety degrees therefrom failing to follow the curvature of the cross-section of the cylinder, but departing therefrom sufficiently to leave clearances c between the ring and cylinder walls, through which the fluid may leak thereby destroying the efficacy of the ring as a packing. By my method a ring of uniform cross-section when finished assumes a truly circular form, exerting a uniform radial pressure against the cylinder walls throughout and being practically proof against leakage.

Referring now to Figs. 3 to 12 inclusive, 3 represents the original pattern ring as cut from an iron tube casting, the outer diameter of which exceeds that of the cylinder bore B as previously pointed out. The next step in the operation is to cut a slit t across the ring with a fine saw thereby splitting or parting the ring as shown. The portions of the ring on each side of the slit are next bent into non-circular form by forcing the same inwardly or radially toward the center of the ring, the free ends thereof under the bending operation being displaced or forced from their original position a distance which, though necessarily varying with the character of the material used, in the present example amounts to substantially one-half the thickness of the ring, this bending action operating to distort the ring into a form or pattern 3' shown by the dotted lines in Fig. 5, and as shown in Figs. 6 and 7. The displacement and distortion are effected in any mechanical manner, but pref-

erably by a machine which gradually strains or bends each section of the ring from the mid section m (the portion diametrically opposite the slit t) to the ends of the ring.

5 The greatest bending is produced in the portions or sections of the ring nearest the ends, the bending or displacement decreasing as we approach the mid section. Thus, assuming (Fig. 7) the point x to represent 10 the geometric center of the ring before distortion, it will be seen that the curvatures of the outer faces of the distorted portions follow, or are defined by, the outer terminals of radii vectors r, r', r'', r''', r'''' , progressively decreasing in length from the 15 ends e, e' of the mid section m , the outside radius of curvature R of which corresponds substantially to the radius of curvature of the outer face of the ring 3 before distortion. 20 The slit t in the pattern 3' is preferably (though not necessarily) closed by a filler h of wax, solder, copper or other material as shown in Fig. 7, the presence of the filler insuring a more rigid pattern. With 25 this distorted ring 3' as a pattern I cast the ring-blank 3'' as shown in Fig. 8. From the blank thus formed I remove a small segment u in the region of maximum displacement, said segment extending on each side 30 of the shortest radius vector r'''' , and corresponding in length substantially to six times the radial displacement of the free ends of the slit ring 3, that is to say, the length of the segment removed is in the 35 ratio of the circumference to the radius along which the displacement was made. By removing the segment u we finally obtain an open ring 4 with a gap o as shown in Fig. 10, such a ring when contracted 40 (and finished) and inserted in the cylinder C contacting with the cylinder walls and exerting even pressure against said walls throughout its entire periphery and making a tight joint with said walls.

45 In the present example, the distortion suffered by the slit ring 3 under the bending operation resulted in a radial displacement of the terminals of the ring of substantially one-half the thickness of the ring; 50 the length of the segment u removed from the distorted ring blank 3'' was equal substantially to six times this radial displacement; the thickness of the ring was given as corresponding substantially to one thirty- 55 second of an inch for each inch diameter of the cylinder bore; the excess of the outside diameter of the original or pattern ring 3 over the diameter of the cylinder was given as one thirty-second of an inch for each inch 60 diameter of the cylinder. These various dimensions and relations, it is to be understood are here given by way of example because frequently occurring in practice; but the same may be departed from by those 65 skilled in the art according to the conditions

to be met. Much depends on the molecular structure of the metal from which the ring blank 3'' is cast; much on the limit of elasticity of the metal; much on the cross-sectional area of the ring; on the resilience of the metal, and on other considerations to be taken into account as they present themselves to the skilled mechanic.

The outside radius of curvature R of the mid section m of the pattern 3' corresponds substantially to the radius of curvature of the outer face of the ring 3 before distortion, that is to say, it is a radius larger than the radius of curvature of the bore B of the cylinder in which the ring is to operate. 75 This radius of curvature progressively diminishes from the mid-section m to a point diametrically opposite the center of said section as apparent from the progressively diminishing radii vectors r, r', r'', r''', r'''' , 80 the shortest radius vector r'''' terminating at the outside of the slit t or the filler h closing the same, as shown. The shortest radius vector r'''' should preferably be a shade less than the radius of curvature of the bore of 85 the cylinder, thereby leaving the radii vectors which lead to the points corresponding to the ends of the outer curve of the segment u removed from the blank 3'' substantially equal to the radius of curvature of 90 the cylinder bore. We thus produce a pattern (Figs. 6, 7,) having on one side a portion or mid section m whose outside radius of curvature is in excess of the radius of curvature of the bore of the cylinder in 95 which the ring is to operate, the radii (vectors) decreasing in both directions from said mid section until they attain a length substantially equal to the radius of curvature of the cylinder bore at points corresponding to the ends of the outer curve of 100 the segment u removed from the blank 3'' cast from said pattern. As previously stated such a pattern and method of producing the same, as well as the ring blank 105 (3'') cast therefrom and the finished ring (4) I consider to be new.

It will be seen from Fig. 5 in which the cylinder bore is represented by the dotted line B , that the radial displacement of the 115 ends of the ring 3 in the process of distortion to form the pattern 3' is sufficient to bring the outer faces of said ends just inside the circle of the bore. From this point the distortion is gradually less until the mid 120 section of the ring 3 is reached where it practically disappears. I do not of course wish to be limited to the precise degree of distortion here shown, any equivalent distortion which will result in a pattern from 125 which a ring blank such as 3'' can be cast and a finished piston ring such as 4 can be obtained falling within the spirit of my invention. It was stated at the outset that a piston ring exerting uniform radial pres- 130

sure against the cylinder walls throughout its entire circumference may be formed by the proper bending and distortion of an original split circular ring, the curvature of 5 the distorted ring being taken from a templet. Such a ring may approach or actually conform to the curvature of the cast ring 4 under my present invention, but besides being open to the objections heretofore 10 pointed out (the consumption of time and labor) it is open to the further objection that its fibers and molecules have been strained in the distorting process, this straining in a measure detracting from the 15 elasticity and resilience of the ring. By my present method I secure a ring 4 of proper contour by casting; and since its molecules have not been disturbed by distortion and bending to bring it into the desired shape, 20 it follows that its elasticity and resilience have not in any wise been impaired or affected. Such a ring (see Fig. 10) comprises a mid section m' whose outer radius of curvature is in excess of the radius of curvature 25 of the bore of the cylinder in which the ring is to operate, conforming in the main to that of the original pattern ring 3, and non-circular side sections s, s , whose outer curvatures follow the terminals of radii 30 vectors progressively diminishing in length from said mid section toward the gap o at which gap they correspond substantially to the radius of curvature of the cylinder bore. These curvatures are eccentric and interior 35 to the outer circle i representing the curvature of the outer face of the original pattern ring 3, and in the main exterior and eccentric to the bore line B. It is to be understood that I do not wish to be limited to the 40 precise relation in the lengths between the radius of the cylinder bore and the shortest radius vector defining the maximum displacement of the ring terminals. A ring in which the shortest radius vector exceeded in 45 length the radius of the cylinder bore would likewise fall within the spirit of my invention. The gap o of course is sufficient to permit the ring to be contracted to a perfectly circular form and to a dimension to 50 permit insertion of the contracted ring into the cylinder C having the bore B. It may be stated in passing that the curve imparted to the slit ring 3 to form the pattern 3' is taken from a templet the curve of which is 55 derived by calculating the stresses at different sections of a hypothetical ring exerting, or assumed to exert, a uniform radial pressure per square inch at all points against the cylinder walls. This templet curve may be 60 imparted to individual split circular piston rings as heretofore described, but as already pointed out this method is laborious, slow, and expensive, and impairs the resilience of the finished ring. It is of course necessary 65 before the ring is put to use that the same

be ground or finished to remove surface irregularities so as to attain a perfectly cylindrical and smooth bearing surface for the ring when inserted into the cylinder. To grind the ring the same is held contracted or 70 compressed in a suitable jig or machine, and while so contracted the same is ground and finished to the proper working condition. The ring thus finished will be perfectly round and true and exert uniform 75 radial pressure at all points against the walls of the cylinder in which it is to operate. For convenience we may assume the ring 4 to have been ground previous to its insertion into the cylinder C as shown in 80 Fig. 11. The invention need not of course be limited to the production of rings for use in pistons and is not to be understood as restricted thereto. The pattern ring 3 and pattern 3' may also be made of brass or any 85 other suitable material. If made of metal it may be readily bent to conform to the templet curve employed, and when once conformed to said curve, the same may be used as a pattern even without the use of 90 the filler h closing the saw slot. With the filler h however we secure a somewhat stiffer pattern. It is apparent of course that I may cut out or remove a segment such as u 95 from the pattern 3' (if made of the proper metal) and secure a piston ring on the order of that herein contemplated, such an alternative falling within the scope of the present invention. But, as pointed out above, this method is not desired in practice involving as it does the individual bending and distortion of each ring, and resulting in a measure in the straining of the fibers from their original condition and reducing the elasticity of the ring. It may be 100 stated in passing that when a circular ring such as 3 is slit and subjected to the distortion here described, to produce the pattern 3', the outside radius of curvature R theoretically begins to shorten or decrease in 105 length from a point diametrically opposite the slit t , so that at this point only does the radius remain its full original length. Practically however the shortening of the radii is not perceptible until the points e, e , are 110 reached, the positions of these points depending of course on the diameter of the ring, the material employed, the cross section of the ring and like factors not necessary to mention. The length of the inside 115 radius of curvature of the ring is controlled in substantially the same way. It is to be understood therefore that what is herein referred to as the mid-section of the ring, is that portion opposite the slit t or gap o 120 whose outside radius of curvature remains practically constant and substantially of the length of the radius R of the ring before distortion, no fixed length of said mid-section being claimed or urged herein. In 125 130

bending the slit circular ring 3 shown in Figs. 4 and 5 into the distorted or non-circular form 3' indicated by the dotted lines in Fig. 5, and as shown in Figs. 6 and 7, the slit 5 contracts somewhat, but the amount is so slight that in order to bring it out, the original width of the slit is purposely exaggerated in Figs. 4 and 5, the contraction clearly appearing in the somewhat narrower dotted 10 line slit in Fig. 5, and in the slit of the ring shown in Fig. 6.

Where the blank 3'' is cast from the pattern 3' provided with the filler *h* the casting will be continuous as shown in Fig. 8. 15 Where the blank is cast from the pattern 3' without the filler as shown in Fig. 6, the continuity of the casting will obviously be interrupted at the slit *t*, the slit in the casting being however in no wise objectionable. 20 Again, the pattern 3' need not be formed by the distortion of a slit circular concentric ring such as 3, it being possible to cut a pattern from a solid plate by following the outlines of a templet ring the curve of which is 25 derived by calculating the stresses at different sections of a hypothetical ring assumed to exert the same radial pressure per square inch at all points against the cylinder walls as previously pointed out, such curve 30 being first plotted on a sheet of paper, and the resulting templet ring thus outlined cut and removed from the sheet and applied to the plate from which the pattern conforming to the templet ring is cut out. It follows therefore that the blank 3'' may be 35 cast from the pattern produced by the latter method the same as it is cast from the pattern 3' produced by the distortion of the circular slit ring 3. Again, to produce the 40 piston ring 4, it is obviously not necessary to first cast the blank 3'' from the pattern 3' or its equivalent, and then remove the segment *u* from said blank; for it must be obvious to those skilled in the art that it is possible 45 to remove a segment such as *u* or its equivalent directly from the pattern (3') and use the resulting open ring as a pattern from which the piston ring 4 may be directly cast. By such a method we produce an open 50 or parted ring which while not in the strict sense a continuous casting is practically so since in the casting operation the metal formed in the gate channels leading from the sprue hole or pouring opening will adhere 55 to the ends of the piston ring casting, this adhering metal as well understood in the art, being readily broken off, leaving the casting in proper condition for the subsequent grinding and finishing operation. A 60 piston ring cast by the last method will be the same product as the ring derived from the blank 3'' after the removal of the segment *u* therefrom according to the method first described. In all cases the ultimate 65 object sought of course is to obtain an open

metal piston ring from a casting of such non-circular or distorted shape that when the ring is compressed to working size the same shall not only assume a circular form but shall exert at all points uniform radial 70 pressure against the walls of the cylinder in which it is intended to operate.

Having described my invention what I claim is:

1. As an article of manufacture, an open 75 metal piston ring comprising a distorted ring casting having a mid section whose outside radius of curvature exceeds the radius of curvature of the bore of the cylinder in which the piston ring is to operate, said 80 mid section being bounded by non-circular sections terminating at the gap of the ring, the outside curvatures of the bounding sections following the outer terminals of radii vectors leading from the center of the outside curvature of the mid section, said radii vectors being shorter than the outside radius of curvature of the mid section, and progressively decreasing in length from the mid 85 section to the free ends of the ring. 90

2. As an article of manufacture, an open metal piston ring comprising a distorted ring casting having a mid section whose outside radius of curvature exceeds the radius of curvature of the bore of the cylinder in 95 which the piston ring is to operate, said mid section being bounded by non-circular sections terminating at the gap of the ring, the outside curvatures of the bounding sections following the outer terminals of radii 100 vectors leading from the center of the outside curvature of the mid section, said radii vectors being shorter than the outside radius of curvature of the mid section, and progressively decreasing in length from the ends 105 of the mid section to the free ends of the ring.

3. As an article of manufacture, an open cast metal piston ring having a mid section whose outside radius of curvature exceeds 110 the radius of curvature of the cylinder in which the piston ring is to operate, said mid section being bounded by non-circular sections terminating at the gap of the ring, the outside curvatures of said bounding sections 115 following the outer terminals of radii vectors leading from the center of the outside curvature of the mid section, said radii vectors being shorter than the outside radius of curvature of the mid section, and progressively decreasing in length from the ends of the mid section to the free ends of the ring, the radii vectors immediately adjacent the gap being substantially equal to the radius of curvature of the bore of the cylinder in 120 which the piston ring is to operate.

4. As an article of manufacture, an open piston ring of resilient and elastic material comprising a distorted ring casting having a mid section whose outside radius of curva- 130

- ture exceeds the radius of curvature of the bore of the cylinder in which the ring is to operate, said mid section being bounded by non-circular sections terminating at the 5 gap of the ring, the outside curvatures of said bounding sections following the outer terminals of radii vectors shorter than the outside radius of curvature of the mid section, and progressively decreasing in length 10 from the ends of the mid section to the free ends of the ring.
5. A piston-ring blank having on one side a curved portion or section whose outside radius of curvature exceeds the radius of 15 curvature of the bore of the cylinder in which the piston ring formed from said blank is to operate, said section being bounded by non-circular portions or sections the outside curvatures of which follow the 20 outer terminals of radii vectors leading from the center of the outside curvature of the first named section and progressively decreasing in length from the ends of said section to a point diametrically opposite the 25 section.
6. A blank for a split metal piston ring comprising a ring having a mid section whose outside radius of curvature exceeds

the radius of curvature of the cylinder in which the piston ring derived from the 30 blank is to operate, said mid section being bounded by non-circular sections terminating at a point opposite the mid section, the outside curvatures of said bounding sections following the outer terminals of radii 35 vectors leading from the center of the outside curvature of the mid section, said radii vectors being shorter than the outside radius of curvature of the mid section and progressively decreasing in length from the 40 ends of the mid section to the meeting point of the bounding sections, the outer face of the portion of the blank extending on opposite sides of the meeting point aforesaid and corresponding to the section removed from 45 the blank to form the piston ring, being bounded by radii vectors corresponding in length substantially to the radius of the bore of the cylinder in which the piston ring is to operate.

In testimony whereof I affix my signature in presence of two witnesses.
